(57) **CLAIM**

The ornamental design for an offset latch cam as shown and described.

DESCRIPTION

FIG. 1 is a first perspective side view of a first embodiment of an offset latch cam;

FIG. 2 is a second perspective side view of the offset latch cam of FIG. 1;

FIG. 3 is a first side view of the offset latch cam of FIG. 1; FIG. 4 is a second side view of the offset latch cam of FIG. 1;

FIG. 5 is a front view of the offset latch cam of FIG. 1; FIG. 6 is a rear view of the offset latch cam of FIG. 1; FIG. 7 is a top view of the offset latch cam of FIG. 1; and, FIG. 8 is a bottom view of the offset latch cam of FIG. 1. Any components in the appended drawings shown in broken lines are for illustrative purposes only and form no part of the claimed design.
